(57) CLAIM

The ornamental design for a pick holder, as shown and described.

DESCRIPTION

FIG. 1 is a top, front, left perspective view of my new design for a pick holder with a pick inserted therein, the pick shown in dotted lines;

FIG. 2 is a top plan view thereof not including the pick inserted therein;

FIG. 3 is a bottom plan view thereof;

FIG. 4 is a front elevation view thereof;

FIG. 5 is a rear elevation view thereof;

FIG. 6 is a left elevation view thereof; and,

FIG. 7 is a right elevation view thereof.

The dotted lines in the drawings illustrate environmental subject matter and form no part of the claimed design.
